UNITED STATES PATENT OFFICE

JOSEPH A. BARTOSZ, OF SALEM, OREGON, ASSIGNOR OF ONE-HALF TO W. J. BRAUN AND
WINONA RICE BRAUN, BOTH OF SALEM, OREGON

RAKE

Application filed April 21, 1931. Serial No. 531,671.

My invention relates to rakes in which flat sheet metal teeth are attached to a backing, and in which the latter is provided with an upwardly extending flange.

5 The objects of my invention are to manufacture a rake of extremely sturdy construction in which the flat metal teeth can be equally well used for ordinary cultivation of soil or for the raking of a lawn, and in which 10 the upwardly extending flange can be used for leveling, weeding or hoeing.

Other objects and advantages are to be found in the construction and arrangement of the parts as will be described in the specification and particularly pointed out in the appended claims.

I attain these objects with the mechanism illustrated in the accompanying drawings, in which:

20 Fig. 1 is a perspective view of a long rake with a low top flange.

Fig. 2 is a perspective view of a short rake with a high and straight top flange.

25 Fig. 3 is an end view of Fig. 2 with the top flange modified into a hoe.

Fig. 4 is a section through Fig. 1 along the line 4—4.

Similar numerals refer to similar parts throughout the several views.

30 The backing is bent of sheet metal in the shape of a Z to combine lightness in weight with a maximum of strength against bending. The downwardly extending front flange 1 furnishes a stop for the quick alinement of 35 the teeth 2 as the latter are spot welded to the web 3 of the backing. The upwardly extending rear flange 4 may vary in height and shape according to requirements. That means: in the case of the long rake, illustrated in Fig. 1, 40 where the rear flange 4 is merely used for the purposes of leveling, said rear flange 4 can be left comparatively low; in the case of the short rake, which is chiefly used for cultivation around growing plants, the height of the 45 rear flange 4 is somewhat increased and either left straight with a sharp edge to serve as a weeder as in Fig. 2, or carried to a sharp point to serve as a hoe as in Fig. 3. The teeth 2 are stamped of sheet metal. The upper edges 50 of each tooth is bent over at right angles,

and spot welded to the web 3 of the backing as shown at 5. The front edge of each tooth 2 is straight and terminates in a raking point at the bottom. The rear edge of each tooth begins with a convex curve at the raking point and terminates in a concave curve flush with the rear flange 4 of the backing. To strengthen the tooth 2 a vertical reinforcing ridge 6 is stamped into the tooth where the same joins the backing. Since the end teeth 2 are most liable to abuse and bending, the web 3 of the backing is bent over at the ends, parallel with the end tooth 2 and spot welded thereto as shown at 7. The socket 8 for the insertion of the handle 9 is a conical shell, 65 split at the smaller end, and the split portion is then flattened at a suitable angle to provide ears 10 with which the socket 8 can be riveted to the web 3 of the backing. The axis of the handle 9 and the front edge of the teeth 70 should preferably form an oblique angle.

Having thus described my invention, it will be seen that my objects have been accomplished, and though I have shown the preferred form of construction, I reserve to myself the right to make minor changes, providing I do not contravene the spirit and principle of my invention.

I claim:

1. In a rake, the combination of a metal 80 backing, comprising a horizontal web, a downwardly extending front flange, an upwardly extending rear flange, and flat metal teeth spot welded to the web of the backing, the plane of said teeth being disposed at right 85 angles to the axis of the web, the front edge of said teeth abutting against the front flange of the backing, the rear edge of said teeth being flush with the rear flange of the backing and a conical socket riveted to the web of the 90 backing.

2. In a rake, the combination of a metal 95 backing, comprising a horizontal web, a downwardly extending front flange, an upwardly extending rear flange having a sharpened edge, and flat metal teeth having a vertically extending reinforcing ridge stamped into said teeth, the upper edge of said teeth being bent at right angles and spot welded to the web of the backing, the ends of said web 100

being bent over at right angles and spot welded to the end teeth, and a conical socket riveted to the web of the backing.

3. In a rake, the combination of a metal backing comprising a horizontal web, a downwardly extending front flange, an upwardly extending rear flange, said rear flange terminating in a sharp point at the center, and flat metal teeth, spot welded to the web of the backing, a conical socket split at the narrow end and extended into ears, said ears being riveted to the web of the backing, the axis of the socket and the front edge of the teeth forming an oblique angle.

15 In testimony whereof I affix my signature.
JOS. A. BARTOSZ.
